GAME

Ed Estes, Uvalde, Tex., assignor of one-half to
Brandon Janes, Uvalde, Tex.

Application April 4, 1933, Serial No. 664,432

2 Claims. (Cl. 273—95)

This invention relates to the class of games or amusement parks and relates particularly to an amusement park designated a hoop ball park wherein a ball and bat is employed in playing a 5 certain laid-out course.

The primary object of the present invention is to provide an amusement structure having at spaced intervals over a predetermined course, an apertured structure through which the player 10 must drive a ball from a predetermined point, the player progressing from one apertured structure to the other.

Another object of the invention is to provide an amusement park in the form of a number of connected alleys which are completely enclosed by wire netting or other suitable covering, whereby a player or players may play through from one end of the alley to the other conveniently and without having the play ball deviate from 20 the laid-out course.

Another object of the invention is to provide in a game of the character herein set forth, a novel target construction whereby the same may be readily dismantled as desired, particularly 25 when the part is out of use for any period of time.

Other objects and advantages of the invention will become apparent as the description of the same proceeds and the invention will be best 30 understood from a consideration of the following detailed description taken in connection with the accompanying drawings forming part of this specification, with the understanding, however, that the invention is not confined to any strict 35 conformity with the showing of the drawings but may be changed or modified so long as such changes or modifications mark no material departure from the salient features of the invention as expressed in the appended claims.

40 In the drawings:—

Figure 1 represents diagrammatically the hoop ball park embodying the present invention, a portion thereof being in top plan to illustrate the top screen covering;

45 Figure 2 is a sectional view taken substantially upon the line 2—2 of Figure 1, showing one of the apertured canvas curtains removed to more clearly show the supporting structure therefor;

Figure 3 is a sectional view taken substantially 50 upon the line 3—3 of Figure 2;

Figure 4 is a sectional view taken substantially upon the line 4—4 of Figure 3;

Figure 5 is a view in side elevation of a portion of one of the covered areas or alleyways;

55 Figure 6 is a view of the canvas supporting

frame guarding one of the passageways past an apertured canvas structure;

Figure 7 is a view in elevation of the canvas which is detachably mounted upon the frame shown in Figure 6;

Figure 8 is a view showing the group of play 5 balls used by one player;

Figure 9 is a plan view of a bat used by a player;

Figure 10 is a sectional view taken substantially 10 on the line 10—10 of Figure 3.

Referring now more particularly to the drawings wherein like numerals of reference indicate corresponding parts throughout the several views, it will be seen upon reference to Figure 1 15 that the amusement or hoop ball park embodying the present invention comprises two alleyways which are indicated by the numerals 1 and 2. These alleyways are preferably laid-off in the manner illustrated, that is, with two side runs 20 and a cross connecting end run. It will, of course, be apparent that it is not essential that this particular design be followed for the proper use of the park for there may be employed a series of longitudinal runs with short connecting runs between the ends thereof where space permits and where an extra long playing area is desired. 25

While there has been illustrated two runways it is also to be understood that the invention is not limited in any manner in this respect. It 30 is preferable that two runways be employed in actual practice, one for the use of adults and the other for the use of children.

In the construction of a single run or alleyway park there would be set up two rows of supporting posts such as are indicated by the numerals 3, connected by cross top rails 4. The runway is then enclosed with wire fabric of a suitable weight, such, for example, as ordinary poultry wire, the same being indicated by the numeral 5. 40 This wire fabric is secured to the outside posts 3 and to the cross connecting rails 4 upon the inner faces thereof so that the posts and cross rails will not interfere with the proper playing of the game. 45

Where a double alleyway is to be constructed, such as is illustrated, the outside posts 3 are suitably spaced apart and a central row of posts 6 is set up and these are connected by wire fabric so that there is thus formed the two runways 50 shown.

While the dimensions of the alleyways may be varied as desired it is preferred that they be approximately ten feet wide and ten feet high and it is also preferred that the posts upon the 55

outside and through the center of the structure be suitably fixed in the ground as, for example, by being set in cement as indicated at 1, so that the structure will remain rigid. To further strengthen the structure the posts may be braced by the brace bars 8 in the manner shown in Figure 5.

As shown, the ends of the runways are open so that free entrance thereto and exit therefrom may be had by the players. Within the runways or alleyways there are set up at spaced intervals vertical frame posts 9 which are disposed between an outer post 3 and a central post 6 or, in a single alleyway between a pair of the outer posts, as is clearly illustrated in Figure 2. These frame posts 9 are located nearer to one of the alleyway posts than to the other, thus forming a narrow passageway 10 and each is connected with the other adjacent alleyway post by a pair of boards 11 which are in spaced relation and horizontally disposed as is also illustrated in Figure 2. These boards may be referred to as bounce boards, for the purpose hereinafter more fully explained. The posts 9 together with the adjacent alleyway posts with which they are connected with the boards 11 and with the overlying alleyway rail 4 and a bottom rail 12, combine to form a target curtain supporting frame which is designated as a whole by the numeral 13. Each of these frames upon one side has the boundary units thereof provided with a series of hooks or eyes which are indicated by the numeral 14, with which are connected coacting hooks or eyes carried by and secured about the edge of a target canvas 15 which is shaped to fit the frame 13 as shown in Figure 2. This target canvas 15 is provided with a target opening 16 which is reinforced by a hoop of rope or other suitable material which is indicated by the numeral 17 and which is secured thereto at the edge of the opening. Upon the side of each target canvas which is approached by the player there is mounted a screen or guard frame 18 before the passage 10. This frame 18 is provided with suitable elements 19 for facilitating the attachment thereto of a canvas screen 20. In the playing of the game this screen serves to prevent the play ball from passing through the passage 10 if the player fails to properly direct the same. It will be seen also, particularly upon reference to Figure 3, that the target canvas 15 overlies the boards 11 upon that side of the same which is approached by the player and it will thus be apparent that a ball driven by the player toward the target canvas and striking just above or just below the opening 16, will contact with one of these boards and rebound.

Directly behind and spaced from each of the frames 13 is a back stop frame 21 which is suitably braced as indicated at 22 and which has removably mounted upon the forward side thereof the canvas back stop 23 which is located directly behind the opening 16 of the target canvas. This back stop canvas 23 is preferably colored in any suitable manner to distinguish it from the target canvas 15 and in addition the back stop frame has mounted upon the top thereof an electric or other suitable type of light which is indicated by the numeral 24 for illuminating the forward surface of the canvas 23 so that when the game is played at night the target opening 16 of each canvas 15 will stand out distinctly before the player's view.

Behind each of the back stops 23 there is placed a marker 25 before which the player stands to

play a ball toward the next target opening. In addition to this marker there is located in each of the areas between a pair of target canvases 15 a marker which is indicated by the numeral 26 and which is designated "penalty marker".

As will be seen upon reference to Figure 1 the distances between the target canvases are varied and the openings in the target canvases are also varied accordingly. For example, where the distance from one target canvas or from one batting position, indicated by the numeral 25, to the next target canvas is long, the opening 16 of the target canvas will be of greater size or diameter than the opening in a target canvas where the distance is less. Figure 2 shows a target canvas having a small opening and another canvas is indicated in dotted lines and shown as having a larger opening.

Each player upon starting the present game is equipped with a bat of the type shown in Figure 9 and indicated generally by the numeral 27, and five play balls such as is shown in Figure 8 and which are indicated by the numerals 28. The bat 27 is preferably constructed of hard rubber and the play balls 28 are formed of sponge rubber and each has a distinctive color marking and a white area bearing an identifying character.

In playing the game the player starts at the first of the markers 25. Each player plays all five balls at each hoop and is permitted one stroke at each ball. The balls numbered one, two and three are known as score balls and each counts according to its number. The ball marked "A" which is preferably maroon colored is known as the record ball and the other ball which is red, white and blue in color is known as the prize ball. At any time that any one of the balls is missed or fails to go through the hoop or bounces back behind the penalty marker 26 the player is penalized. The score balls are the only balls that count off on fouls, bounce back or when entirely missed by the bat and they count off according to their numbers. If the record and prize balls are missed, or bounce back, they are dead balls for that hoop. The maroon or record ball is played to off-set all of the bounce balls at each hoop. If the hoop is made with the record ball it clears the record of all bounce balls at that hoop and if there are no bounce balls it is played to count above par score and to untie a tie score.

The red, white and blue ball is played at each hoop and counts the same as the high score ball at that hoop. If no score is made it is played and if made the score will count the same as the high score at the next hoop only and if made at the next hoop the score is carried on to the next hoop and likewise throughout the course except at the thirteenth hoop. Number thirteen hoop stands out to itself and must be made to count. If made with the prize ball the count is five, and if in the hole up to number thirteen hoop all back record is cleared up, giving you a five score count to your credit. If prize ball scores at number twelve the count is carried over to number fourteen, if there are no score balls made at number twelve. No credit is carried to or from number thirteen, with the prize ball as at other hoops. The letters on the balls are for the players to distinguish their balls.

Players may play in twosomes, threesomes, or foursomes, or in case of large teams they may pass through in grouped foursomes, each player having all balls of the same letter. The total high score of the score balls, number one, two and three is always counted the winner.

Par score.—When all score balls number one, two and three, and red, white and blue balls are made through the hoop the par score is nine for all hoops except number thirteen. The score 5 balls number one, two and three, at number thirteen are the same as at all other hoops, and the red, white and blue ball count is five at number thirteen hoop, making par score at number thirteen, eleven, making a total par score 200, 10 and the record ball counts one at each hoop made, making twenty-two above par. That is all that can be made.

Having thus described the invention, what is claimed is:—

- 15 1. Apparatus for playing a game of the character described with a ball and bat, comprising an enclosed alleyway, a plurality of partition-like structures disposed at spaced intervals along said alleyway and extending transversely thereof 20 from one side to and terminating short of the other side whereby to provide passages therepast, each of said structures having an opening constituting a target toward which a ball is batted by a player, a guard partition extending from 25 the other side of the alleyway and disposed forwardly of each of said passages and transversely of the alley-way to prevent a driven ball passing through the passage, a position indicator at the

rear of each of said first partitions from which a player bats the ball to the next target opening, a back stop structure disposed rearwardly of each of said first mentioned partitions to limit the flight of a ball passing through the opening of the adjacent partition, and illuminating means upon each of said back stops disposed to illuminate the forward face of the same whereby the aperture in the adjacent partition will be clearly distinguished for a player facing the same. 5

2. In apparatus for playing a game of the character described with a bat and ball, including an enclosed alleyway having an entrance and an exit, a partition-like frame disposed in the alleyway and extending transversely thereof, a body of 15 flexible material secured to said frame and having an aperture constituting a target toward which a ball is driven, a board extending across the frame in back of and in contact with said body of material and in relatively close proximity 20 to said aperture, said board constituting a reinforcing for the flexible material against which a mis-directed ball may strike, and means disposed in the alleyway in advance of said body of material constituting a penalty marker for 25 a ball rebounding from said board.
